UNITED STATES PATENT OFFICE.

SAMUEL McCARTER, OF NORRISTOWN, ASSIGNOR OF ONE-HALF TO BENJAMIN F. ASPER, OF PITTSBURG, PENNSYLVANIA.

MINING-MACHINE.

SPECIFICATION forming part of Letters Patent No. 349,731, dated September 28, 1886.

Application filed September 7, 1885. Serial No. 176,397. (No model.)

To all whom it may concern:

Be it known that I, SAMUEL McCARTER, a citizen of the United States, residing at Norristown, in the county of Montgomery and State of Pennsylvania, have invented certain new and useful Improvements in Channeling-Machines for Coal, Stone, &c.; and I do hereby declare the following to be a full, clear, and exact description of the invention, reference being had to the accompanying drawings, which form part of this specification, in which—

Figure 1 is a side elevation. Fig. 2 is a plan. Fig. 3 is an inverted bottom view; and Fig. 4 is a vertical detail section enlarged.

My invention has for its object to provide a machine primarily designed to be operated by hand, and to be used for the purpose of channeling coal, stone, and other materials usually obtained by mining or quarrying.

Heretofore the operations of mining and quarrying have been usually effected by means of a pick manually used, or by drills operated by steam or other mechanical power. The pick requires skill for its effective use and is slow and difficult in operation, while power machinery is expensive and usually cumbrous.

My invention aims to provide a device which will require only the same power as the pick, but can be operated by unskilled labor, and will do a much larger amount of work than a pick will in the same time. My invention, accordingly, provides a machine which is the miner's friend in that it increases the production by his hands, while lessening his laborious efforts; and it is also an efficient auxiliary of the operator or producer, as it enables him to employ unskilled labor and to secure an increased output at lowered rates.

My invention consists of a machine adapted and designed to impart motion to a flexible or jointed cutter—such as a toothed wire or a chain-saw composed of links having cutting-teeth—and to feed the same forwardly as the cut deepens, substantially as hereinafter fully set forth.

Referring to the accompanying drawings, A designates the base or bed-piece of the machine, which may be a casting, either gray or malleable iron or steel, or it may be wholly or part-

ly of wood. Said base is oblong in form, having two side bars, a a' , and two end pieces, a^2 a^3 , leaving a central longitudinal slot or opening, B. C represents a carriage or slide designed and adapted to traverse said slot, said slide having grooved sides which move upon the inner edges of the side bars, a a' , the latter serving as guides or ways. To the forward end of the slide is adjustably secured an extension, D, consisting of a bar supported in keepers or lugs d d , on the under side of the bed A, so that the slide and its extension will move together. On the slide extension D there is a cross-head, E, composed of two plates, E' E' , between which are pulleys e e . The slide has a central standard, F, which affords bearings for a vertical shaft, G, and it has a bifurcated head, F', which sustains a shaft, H, from which, through the medium of bevel-gears g h , motion is communicated to said shaft G. Shaft H is provided with two crank-handles or wrenches, h' h'' , by which it is turned; or power may be applied from a steam or other engine or electric motor to secure the revolution of said shaft. On the lower end of shaft G there is made fast a pulley, I, over which and the pulleys e e a chain-saw, K, or other flexible cutter runs. K' is a guard plate to keep said cutter on the pulley I. Said shaft G has also a worm, G', which meshes with a worm-wheel, l, on a transverse shaft, L, having its bearings in a box, l', on the base of slide C. Said shaft L carries a pinion, M, which meshes with a rack, N, sustained on and fastened to the bed-piece A. This pinion M is normally loose on shaft L, but rests between two friction-collars, O O', which are secured on said shaft L, so as to always move therewith. The inner collar, O, is stationary on shaft L, but the outer collar, O', is movable laterally or axially on said shaft, so as to clamp said pinion M with more or less friction between both collars, a thumb-nut, o, being provided to move said collar O'. By varying the pressure the friction may be increased or lessened, this construction thus forming an adjustable friction-feed for the slide, its extension, and the cutting device. If the pinion M be left loose on shaft L, when the shaft H is turned the cutter will run without

feeding forward. If said pinion be clamped between the collars, it will turn with them, and, by reason of its engagement with the rack N, cause the slide C to be moved forwardly, carrying with it the extension D and the cutting saw chain or tool. By adjusting the friction the feed may be varied—that is, increased or lessened in speed—and the friction may be so graduated that in case the cutter meets with an usually hard projection the feeding motion will be stopped or suspended, the pinion M slipping on its shaft as long as the resistance to the feed or advance of the cutter is more powerful than the friction of the feed-clutch. The base A is supported on feet p p, which may consist of adjustable screw-pins or pointed bolts, which rest on the ground or floor of a mine when the machine is in use and placed horizontally. When so placed, the miner or operator sits on the rear end of the machine and works the cranks with his hands, advancing his position on the bed-piece as the feed progresses, the machine being bodily moved in a lateral direction after it cuts in as deeply as it will in order to make a fresh cut or widen the cut just made. If the machine be used, as it may be, for shearing or side cutting, the base will then be placed edgewise or in a vertical plane, and may be guided vertically on posts or rods passing through eyes q q on said base.

To permit the handles to be readily and conveniently turned when the machine is shearing, the upper part, F³, of the standard F should be swiveled on the lower part, F², and be turned around, so as to cause said handles, when turned, to move in planes transverse to the length of the machine, said upper part being made fast by set-screws f f, as shown in the drawings.

To permit the saw-chain or cutting device to be put on and taken off the pulleys, the nuts on the bolts d' d', which pass through slots d² in the extension D and fasten said extension to the slide, are first loosened to permit the extension to be moved back on the slide. After the chain-saw is put on, the extension is moved forwardly on the slide until the requisite ten-

sion of the chain-saw is secured, and the nuts are then tightened on their bolts. 50

What I claim as my invention is—

1. The combination, in a mining-machine, of a bed-piece of oblong form having a central longitudinal slot and a rack located on its upper-surface, a carriage arranged to slide in said slot and having an extension which carries pinions or sprocket-wheels at its forward end, a pulley-wheel supported by said carriage, a toothed chain which passes around said pulley, and a pulley or pulleys on said extension, a vertical power-shaft provided with a worm, and pinions engaging, respectively, with said worm and with the rack on the bed-piece, and mechanism, substantially as described, for imparting motion to the power-shaft, and thereby 65 operating the cutting and feeding mechanism, as set forth.

2. In a mining-machine, the combination, with the bed-piece and a traveling carriage or frame supported thereon and carrying a toothed-chain cutter, of a rack mounted on said bed-piece, and mechanism for imparting motion to the cutter and feeding the same forward, said mechanism comprising a pinion secured to its moving shaft by means of a collar, O, rigidly secured to said shaft, a movable collar, O', and a thumb-nut, o, constituting a frictional clamp for said pinion, the latter engaging with said rack and receiving motion from the power-shaft of the machine, substantially 80 as described.

3. The combination, with base or bed piece A, having central longitudinal slot B, of carriage or slide C, which moves in said slot, pulley I, attached to said slide, and extension D, 85 also secured to said slide and having at its forward end a cross-head or bearing, E, for pulleys e e, substantially as shown and described.

In testimony that I claim the foregoing I have hereunto set my hand this 26th day of 90 August, 1885.

SAML. McCARTER.
